CARDING MACHINE

Charles E. White, Abington, Mass., assignor to
Abington Textile Machinery Works, Abington,
Mass., a trust of Massachusetts

Application July 8, 1947, Serial No. 759,542

8 Claims. (Cl. 19—109)

1

This invention relates to improvements in methods and mechanisms for stripping the mat of material which accumulates upon the surface of a rotating carding cylinder and/or that which accumulates upon the doffer cooperating therewith for the purpose of producing a sliver of uniform character and quality.

Usual mechanisms for stripping the mat of material which accumulates upon the surface of a continuously rotating carding cylinder comprises a carriage having stripping mechanism, preferably of the pneumatic type, which is moved during the stripping operation longitudinally of a cylinder and/or a doffer of a carding machine by a traverse screw extending longitudinally of the machine and having a thread of uniform pitch which is engaged by a pawl on the carriage after the carriage has been moved manually to initial stripping position at one end of the cylinder and/or doffer and which is moved by the rotation of the traverse screw at a uniform speed of rotation to cause the carriage to travel lengthwise of the cylinder and/or doffer with means automatically operable to release the carriage from engagement with the traverse screw upon the completion of the traversing movement.

Inasmuch as the traverse of the carriage begins at once upon engagement of its pawl with the traverse screw it has heretofore been necessary for the operator to hold the carriage in initial stripping position a sufficient time to insure complete stripping of the initial end of the cylinder and/or doffer before the pawl on the carrier is engaged by the traverse screw, for if the pawl is immediately engaged with the traverse screw when moved to initial stripping position the traverse of the carriage will begin immediately to strip the continuous spiral furrow beginning at the initial end of the cylinder and will leave a triangular unstripped portion or dog tail between the first turn of the spiral and the initial end of the cylinder. Similarly, if the pawl of the carriage is immediately released at the terminal or finishing end of the stripping operation a similar triangular unstripped portion will remain upon the terminal end of the more slowly rotating doffer.

The general object of the invention is to provide a method and means for insuring complete stripping of the cylinder throughout its entire length without necessitating the delay heretofore required to insure complete stripping of the end portions of the cylinder and/or doffer.

In prior machines when the carriage has moved to the terminal or finishing end of the cylinder

2

and arrested a further delay has been required to complete the stripping of the terminal end of the more slowly rotating doffer before suction upon the nozzles is cut off and where the valve and suction pipe is manually operated to cut off suction additional attendance is required by the operator to that for holding the carriage during the stripping of the initial end of the cylinder before the feeding of material to the cylinder is resumed.

10 I am aware that means have been devised for automatically discontinuing the application of suction to the nozzles and thereupon causing the resumption of the feeding mechanism, but in any case attendance of the operator is required properly to strip the initial end of the cylinder.

Inasmuch as in the carding room or department of a textile plant an operator is required to attend several machines the lost time in the attendance of each machine although short will, 20 during a day's operation, accumulate to a considerable amount and may cause the interruption of operation of other machines. One of the objects of the invention is to avoid such wastage of time upon the part of the operator and to provide a system in which the commencement of the stripping of each machine may be begun promptly upon the completion of the previous stripping thereby enabling the machine to produce a sliver of carded material of uniform character and quality.

Where, in usual pneumatic stripping apparatus heretofore employed, the suction is immediately cut off at the end of the traverse of the carriage the fibrous material in the pipe intermediate of the nozzle and suction controlling valve tends to accumulate upon and interfere with the operation of the suction valve mechanism.

A further object of the invention comprises a method and apparatus by means of which such 30 relatively narrow adjoining spirals of material will be stripped from the initial end of the cylinder and/or the terminal end of the doffer as will avoid the likelihood of clogging the suction controlling valve when the carriage is arrested at 40 the end of the stripping operation.

Another object of the invention is to provide pneumatically operable stripping mechanism for repeatedly stripping the cylinder in sequence without interruption of the continuous operation 50 of the carding cylinder and doffer, it being understood that suitable means are provided for discontinuing the feeding of the material to the cylinder during the stripping operation and for causing the resumption of feed immediately at 55 the end of the stripping operation.

The invention comprises suitable mechanism for decreasing the rate of traverse of the carriage at the initial and terminal portions of the stripping operation which is adapted to be embodied in a card stripping mechanism of the type disclosed in the prior Patent No. 2,281,344 granted to me April 28, 1942, for improvements in Carding machines. A sufficient portion of the mechanisms adapted to be so embodied in the card stripping mechanism of the aforesaid type is illustrated in the accompanying drawing, in which,

Fig. 1 is a view partially in vertical section illustrating the traversing mechanism for the carriage embodying the present invention with the pawl on the carriage in engagement with the traverse screw; and,

Fig. 2 is a similar view illustrating the pawl on the carriage disengaged from the threads of the traverse screw at the terminus of the stripping operation.

Fig. 3 is an end elevation of a portion of the card stripping mechanism;

Fig. 4 is a front elevation of the left hand end of the main cylinder of the carding machine with the suction nozzle at the end of the traverse;

Fig. 5 is a detail in cross section taken on the line 5-5 of Fig. 3, illustrating the suction valve in open position.

Earlier types of pneumatic card stripping mechanism comprise a carriage reciprocably mounted upon a suitable guide extending longitudinally of the cylinder and doffer and provided with nozzles having mouths cooperating respectively with the peripheries of the cylinder and doffer.

To perform the stripping operation the carriage was moved manually to one end of the cylinder, the mechanism for feeding material to the cylinder rendered inoperative, means manually operated to apply suction to the stripping mechanism, the pawl and the carriage thereupon engaged with a traverse screw having threads of uniform pitch extending throughout its length operable to move the carriage and its nozzles longitudinally of the cylinder and doffer at a uniform speed. As the carriage reached the end of the stripping operation the pawl and the carriage were disengaged from the traverse screw, the valve through which suction is applied to the nozzle manually closed, and the mechanism for feeding the material to the cylinder then manually restored to operative position to resume the carding operation. In later improved machines, such as that disclosed in my prior patent aforesaid, automatically operable means were provided for discontinuing the application of suction and thereafter for causing resumption of the mechanism for feeding material to the carding cylinder. However, means were provided for permitting the suction to remain on after the carriage had been stopped for such predetermined time as was necessary to cause complete stripping of the terminal end of the cylinder and particularly of the doffer. In all cases, however, it was necessary to hold the carriage at the initial end of the stripping operation after suction had been applied before the pawl and the carriage was engaged with the traverse screw to insure complete stripping of the initial end of the cylinder.

In all cases considerable time of the operator is required to attend to the stripping of the initial end of the cylinder and continuation of the suction after the carriage had been stopped at the

terminal end of its movement was required to complete stripping of the cylinder and doffer.

Ordinarily an operator attends to the stripping of several adjacent machines and the number of machines undergoing stripping at any one time is limited by the capacity of the suction system. It is therefore important to take a stripped machine off the suction line as soon as possible after its stripping operation has been completed in order that stripping may be started on another machine without overloading the suction mechanism. It is also important that the stripped machine be restored to carding with a minimum of delay.

By reason of the present invention the stripping operation can be initiated immediately when the carriage is moved by the operator to initial stripping position and when the carriage is arrested at the end of the stripping operation suction immediately cut off thereby not only saving time of the operator but also conserving the power required for the suction mechanism.

The carriage traversing mechanism of a pneumatic card stripper for stripping the carding cylinder 1 and the doffer 2, which are graphically illustrated in the drawings, comprises the usual tubular guide 3 for the carriage which is mounted upon suitable brackets 4 and 5 which are respectively mounted upon the side frames 6 and 7 of the carding machine. The carriage 8 is slidably mounted upon the guide 3 and is provided with a suction chamber 9 to which suction is applied through the usual flexible pipe. The carriage is provided with usual suction nozzles 10 positioned respectively in stripping relation to the carding cylinder and the doffer. The traverse screw is provided with cylindrical portions 10 and 11 which are mounted respectively in bushings 12 and 13 in bosses 14 and 15 on the brackets 4 and 5. The traverse screw is connected at one end to a pinion 16 which is driven by a gear mounted on the doffer shaft as illustrated in my prior patent aforesaid.

The traverse screw is provided throughout the greater portion of its length by a main thread 17 of suitable pitch as is usual in prior constructions.

In the present invention the initial end portion of the traverse screw has threads 18 of uniform lesser pitch, preferably approximately half the pitch of the main screw, and the terminal end of the traverse screw is likewise provided with similar threads 19 of uniform lesser pitch preferably equal to those of the section 18.

The carriage 8 has pivotally mounted upon it a pawl 20 which is provided with a replaceable hardened plate 21 which engages the threads of the traverse screw. The opposite arm 22 of the pawl is of arcuate form and is adapted to ride upwardly upon the reversely curved surface of a pawl-lifting arm 23 which is adjustably mounted in the bracket 5 and serves when the carriage reaches the finishing end of the stripping movement to disengage the pawl from the traverse screw.

As heretofore described means have been designed as exemplified in my prior patent aforesaid to delay the shutting off of the suction upon the nozzles until the terminal end of the doffer cylinder has been completely stripped and means thereupon actuated to cause resumption of the feeding of material to the carding cylinder. Such mechanisms for producing a delayed closing of the suction valve are of a complicated character and if actuated promptly upon arrest of the car-

riage permit the retention between the valve and suction nozzle of accumulated fibres which clog or otherwise interfere with the operation of the suction valve. By reason of the present invention the reduction of material in the narrower furrows at the terminal portion of the stripping operation enables the shut-off valve in the suction pipe to be immediately closed at the end of the stripping operation in such manner as to avoid an accumulation in the suction pipe which will interfere with the operation of the suction valve.

Suitable mechanism for thus promptly closing the suction valve at the end of the stripping operation is clearly disclosed in my Patent No. 2,464,425 granted March 15, 1949, on an application filed June 2, 1947, and Figs. 3, 4, and 5 of the drawings correspond to Figs. 1, 2, and 3 respectively of the drawings of the said Patent No. 2,464,425. In this construction, as is usual, suction is applied to the nozzle 30 for the main cylinder and the nozzle 31 for the doffer through a suction pipe 32 terminating in the suction chamber 9 of a suitable valve casing 33. In this valve casing is slidably mounted a valve, shown as an apertured plate 34, normally held in the open position shown in Fig. 5 against the tension of the spring 35 by a suitable detent. This detent is shown as a bell crank lever 36 fulcrumed at 37 on the valve casing with its shorter arm, when the valve is in open position, extending in front of the edge of the retracted valve plate 34 and held in position by a pin 38 projecting from the valve casing. The means shown for releasing this detent and thus shutting off the suction from the nozzles at the end of the traversing movement of the carriage, is as illustrated in the aforesaid Patent No. 2,464,425. During the traversing movement of the nozzle 30 this nozzle rides beneath a cover 40 for the slot in the cylinder casing held in open position against the tension of a spring 41. At the end of the traversing movement the nozzle passes opposite a notch 42 in the edge of the cover and engages and swings a latch 43 which by engagement of the shoulder 44 with the edge of the notch 30 has held the cover in open position against the tension of the spring 41. This closing movement of the cover is utilized to release the detent 36 and shut off the suction. In the construction illustrated a shipper rod 45, sliding in a guide 46 supported from the bracket 5, has adjustably mounted at one end a striker 47 located behind the longer arm of the bell crank lever 36 and at its other end is pivotally connected to a projection 48 secured to the cover 40. Thus it will be seen that at the end of the traversing movement of the stripping mechanism the longer arm 36 of the bell crank lever will come in front of the striker 47 and simultaneously the latch 43 will be swung to release the cover and the cover in turn will move the shipper rod 45, thus to unlatch the detent and allow the spring 35 to slide the valve plate 34 to closed position, thus shutting off the suction.

In the operation of the machine the threads of lesser pitch at the initial and terminal end portions of the traverse screw reduce the rate of traverse of the carriage relatively to that produced by the coarser threads 17 of the traverse screw, thereby causing the stripping of a greater number of adjoining narrow furrows at the initial and terminal ends of the stripping operation over the number of wider furrows stripped throughout the greater portions of the cylinder

and doffer respectively, thereby insuring complete stripping of the initial and end portions of the mat upon the cylinder and doffer respectively without leaving any unstripped dog tails.

5 By reason of this construction the operator is permitted immediately to engage the pawl on the carriage with the traverse screw to begin the stripping operation after he has discontinued the operation of the feeding mechanism and 10 caused the application of suction to the nozzle. He may then leave the machine to attend to other machines of which he has charge. When the carriage has reached the finishing end of the traverse the threads of lesser pitch on the traverse screw cause the suction nozzles to produce relatively narrow furrows containing less material so that when the carriage is arrested at the end of its traversing movement the shut-off valve in the suction pipe may be immediately closed without danger of accumulation of material in the suction pipe which will interfere with the operation of the suction valve and the operation of the mechanism for feeding material to the carding cylinder immediately resumed.

15 25 By reason of the present invention therefore a considerable saving of time of the operator is effected and the consumption of power in operating the suction system reduced to a minimum.

It will be understood that the particular mechanism shown and described herein for performing the method and accomplishing the purpose of the present invention is of an illustrative character and not restrictive of the meaning and scope of the following claims.

30 35 Having thus described the invention, what is claimed as new, and desired to be secured by Letters Patent, is:

1. Card stripping mechanism, for removing the 40 mat of material accumulated upon the surface of a continuously rotating cylinder, a carriage having stripping means and traversing means for moving the carriage longitudinally of the cylinder in proximity to the carding surface thereof at a uniform normal rate progressively to remove adjoining furrows of material from said mat throughout the greater portion of the length of the cylinder and having means for decreasing the rate of traverse of the stripping means at the initial portion of said traverse thereby to insure complete stripping of the mat from that end of the cylinder.

2. Card stripping mechanism, for removing the 45 mats of material accumulated upon the surfaces of a continuously rotating cylinder and doffer, a carriage having stripping means and traversing means for moving the carriage longitudinally of the cylinder in proximity to the carding surface thereof at a uniform normal rate progressively to remove adjoining furrows of material from said mats throughout the greater portion of the length of the cylinder and having means for decreasing the rate of traverse of the stripping means at the initial and terminal portions of said traverse thereby to insure complete stripping of the mats from those ends of the cylinder and doffer.

3. Pneumatic stripping mechanism, for the 50 cylinder of a carding machine, having a carriage provided with a suction nozzle and means for guiding said carriage lengthwise of the cylinder with the end of the nozzle in close proximity to the carding surface thereof to remove the material accumulated thereon, means for moving the carriage lengthwise of the cylinder including a traverse screw rotating in suitable

timed relation to the rotation of the cylinder and having the greater portion of its length provided with a main thread of suitable pitch to cause the nozzle progressively to strip narrow adjoining furrows of material from the mat of material on the cylinder at a predetermined rate and having at its initial end a thread of less pitch merging into the main thread acting so to decrease the rate of traverse of the carriage as to cause the nozzle completely to strip the material from the corresponding end of the cylinder.

4. Pneumatic stripping mechanism, for the cylinder and doffer of a carding machine, having a carriage provided with suction nozzles and means for guiding said carriage lengthwise of the cylinder with the ends of the respective nozzles in close proximity to the cooperating surfaces of the cylinder and doffer to remove the material accumulated thereon, means for moving the carriage lengthwise of the cylinder including a traverse screw rotating in suitable timed relation to the rotation of said cylinder and doffer respectively and having the greater portion of its length provided with a main thread of suitable pitch to cause the nozzles progressively to strip narrow adjoining furrows of material from the respective mats of material accumulated on the cylinder and doffer at a predetermined rate and having at its initial and terminal ends respectively threads of less pitch merging into the main thread acting so to decrease the rate of traverse of the carriage as to cause the nozzles completely to strip the material from the corresponding ends of the cylinder and doffer.

5. Pneumatic stripping mechanism, for the cylinder and doffer of a carding machine, having a carriage provided with suction nozzles, means for guiding the carriage lengthwise of the cylinder and doffer with the ends of the respective nozzles in close proximity to the cylinder and doffer, a suction pipe communicating with said nozzles provided with a shut-off valve, traversing means for moving the carriage lengthwise of the cylinder and doffer while suction is applied to the nozzle to cause the nozzles to strip adjoining spiral furrows of material from the cylinder and doffer respectively, means for arresting the traverse of the carriage upon completion of the traversing movement and means operable thereupon to close the shut-off valve, comprising means for so coordinating the rates of traverse of the nozzle to the peripheral speeds of the cylinder and doffer as to cause the nozzles to strip spiral furrows of uniform predetermined width throughout the major portion of said traverse and at the terminal end portions of said traverse to strip relatively narrow adjoining furrows thus reducing the amount of material drawn into the suction pipe sufficiently to avoid clogging or interference with the operation of the suction valve.

6. Pneumatic stripping mechanism, for the cylinder and doffer of a carding machine, hav-

ing a carriage provided with suction nozzles, means for guiding the carriage lengthwise of the cylinder and doffer with the ends of the respective nozzles in close proximity to the cylinder and doffer, a suction pipe communicating with said nozzles provided with a shut-off valve, traversing means for moving the carriage lengthwise of the cylinder and doffer while suction is applied to the nozzle to cause the nozzles to strip adjoining spiral furrows of material from the cylinder and doffer respectively, and means for actuating the shut-off valve upon completion of the traversing movement, said traversing mechanism comprising a traverse screw having throughout the major portion of its length a thread of uniform pitch adapted to cause said nozzles to strip adjoining furrows of predetermined width from the mat of material upon the cylinder and doffer and provided with end portions having threads of lesser pitch to cause the stripping of relatively narrow adjoining furrows, thus reducing the material drawn into the suction pipe sufficiently to avoid clogging or interference with the operation of the suction valve.

7. A traverse screw, for propelling the carriage of a card stripping mechanism longitudinally of the cylinder or cylinders of the carding machine, having a main section provided with a thread of predetermined uniform pitch extending throughout the greater length thereof, and a relatively short end section provided with a thread of uniform less pitch merging into said main thread adapted to reduce the rate of traverse of the carriage to insure complete stripping of that end portion of the cylinder.

8. A traverse screw, for propelling the carriage of a card stripping mechanism longitudinally of the cylinder or cylinders of the carding machine, having a main section provided with a thread of predetermined uniform pitch extending throughout the greater length thereof, and relatively short initial and terminal end sections provided respectively with a thread of uniform less pitch merging into said main thread adapted to reduce the initial and terminal rate of traverse of the carriage to insure complete stripping of both end portions of the cylinder.
